COMBINATION VEHICLE HOOD ORNAMENT AND DEFLECTOR

Harry A. Reichman, Chicago, Ill.

Application October 18, 1951, Serial No. 17,005

Term of patent 7 years

(Cl. D14—6)

To all whom it may concern:

Be it known that I, Harry A. Reichman, a citizen of the United States, residing at Chicago, in the county of Cook and State of Illinois, have invented a new, original, and ornamental Design for a Combination Vehicle Hood Ornament and Deflector, of which the following is a specification, reference being made to the accompanying drawing, forming a part hereof.

In the drawing:

Fig. 1 is a front perspective view of a combination vehicle hood ornament and deflector embodying my new design;

Fig. 2 is a front elevational view thereof;

Fig. 3 is a top plan view of the same;

Fig. 4 is a rear elevational view thereof; and

Fig. 5 is a side elevational view of the same.

The dominant feature of my design is that shown in the full lines on the drawing.

I claim:

The ornamental design for a combination vehicle hood ornament and deflector, substantially as shown and described.

HARRY A. REICHMAN.
